UNITED STATES PATENT OFFICE.

FRANK G. FEELEY, OF CHICAGO, ILLINOIS, ASSIGNOR TO M. D. KNOWLTON COMPANY, OF ROCHESTER, NEW YORK, A CORPORATION OF NEW YORK.

LOCKING DEVICE.

1,138,368.

Specification of Letters Patent.

Patented May 4, 1915.

Application filed July 5, 1913. Serial No. 777,530.

To all whom it may concern:

Be it known that I, FRANK G. FEELEY, a citizen of the United States, and resident of Chicago, in the county of Cook and State of Illinois, have invented certain new and useful Improvements in Locking Devices, of which the following is a specification.

My invention relates to locking devices of the type disclosed in Letters Patent No. 974,156, issued Nov. 1, 1910, and which are particularly adapted for use in adjustably securing the rotary cutting and creasing devices used in paper-board working machinery, on their supporting mandrels.

As disclosed in the aforesaid patent, the collar or hub member which carries the rotary cutting or creasing device is provided with a bore tangential to the mandrel opening and intersecting the same to provide a communicating opening; and in said bore is located a locking device comprising a compression bolt and three sleeves thereon having adjacent co-acting faces inclined in a direction whereby the central sleeve, under endwise compression by the adjacent sleeves, will be moved transversely of the bolt to a position in clamping engagement with the mandrel and so effect the locking of the cutting or creasing collar to said mandrel. In order that the central clamping sleeve may effect a secure clamping engagement with the mandrel, its under side is curved in a direction transversely of the mandrel to conform to and closely fit upon an extended surface of said mandrel.

To operate this locking device, that is, to effect the tightening or loosening of the central clamping sleeve in its relation to the mandrel, the operator turns the compression bolt in the proper direction by means of a wrench or similar tool applied to the end of the bolt. In doing this, experience has shown that there is a decided tendency on the part of the operator to exert endwise pressure against the bolt, which frequently results in a gradual forcing of the clamping sleeve to the far side of the mandrel and a consequent canting of the same on the bolt whereby it will be caused to bear at one point only on the mandrel when forced into clamping engagement therewith. This obviously results in an insecure clamping engagement with the mandrel and at the same time has a

tendency to mar and roughen the mandrel surface. To avoid this has been the object of my present invention, to which end the invention consists in loosely connecting the mandrel clamping sleeve of the locking device with the collar or hub member of the cutting or creasing device in which it is carried in a manner whereby it will be held centrally of the mandrel while being free for lateral or transverse movement to and from its clamping position.

Referring now to the accompanying drawings forming part of this specification,—Figure 1 is a transverse section through a mandrel having a cutter secured thereto by means of a locking device embodying my invention, the locking device and the collar or hub of the cutter adjacent to said locking device being in section to more clearly show the construction and operation of the parts. Fig. 2 is an elevation of the parts shown in Fig. 1, looking from the right-hand side thereof. Figs. 3 and 4 are views corresponding to Figs. 1 and 2, respectively, and illustrating a modified form of the invention. Figs. 5 and 6 are similar views illustrating another modified form of the invention. Fig. 7 is a central transverse section through the central clamping sleeve of the locking device.

Similar reference characters indicate like parts on the several figures of the drawings.

The collar or hub member 1 which carries the cutter or other similar device 2 is formed with a bore 3 tangential to the mandrel-receiving opening or main bore 4 and intersecting the same to provide a communicating opening. In this bore 3 is located the locking device which comprises the compression bolt 6 and the three sleeves 7, 8 and 9, mounted thereon, the central one of which, indicated at 8, being formed with an opening or bore of greater diameter than that of the bolt whereby it may be moved laterally of the bolt through the communicating opening between the bores to a position of clamping engagement with the mandrel, indicated at 10. To effect such lateral movement of the clamping sleeve 8, the adjacent ends of the three sleeves are inclined, as at 11, 11, in a direction whereby the central or clamping sleeve will be moved laterally of the bolt and to its said position of clamping engagement

with the mandrel under endwise pressure by the end sleeves. This endwise pressure may be exerted by any suitable means, the same as here shown being exerted by the bolt 6 which is threaded at one end into the end sleeve 9 and at its opposite end has a thrust-head 12 engaging the other end sleeve 7, in the manner illustrated. A square stud or head 13 at the front end of the bolt permits of its engagement by a wrench or other operating tool.

In order to hold the central or clamping sleeve 8 against endwise movement in the bore 3 and centrally of the mandrel, in the manner and for the purpose hereinbefore referred to, any suitable means may be employed. As shown in Figs. 1 and 2, it is so held by means of a screw 14 threaded into the collar 1 with its inner or lower end 20 loosely engaging the sleeve within an opening 15 therein. This connection holds the sleeve against endwise movement while permitting of its necessary lateral movement on the bolt. In Figs. 3 and 4 is shown a similar holding means comprising a pin 16 in the collar loosely engaging the clamping sleeve within a slot or groove 17 therein. In Figs. 5 and 6 is shown another holding means comprising a spring 18 connected to 30 the clamping sleeve and having a projection 19 at its upper side which engages the collar 1 within a seat or opening 20. These several different means for holding the clamping sleeve of the locking device centrally of the mandrel are merely illustrative of a few of the various means which may be employed for the performance of the described function and be within the scope of the invention and defined in the following 40 claims.

What I claim is:—

1. In combination with a member provided with a bore having a lateral opening, of a locking device located in said bore comprising a plurality of parts having co-acting inclined faces and one of which parts is movable laterally of the bore under endwise compression by the other, compressing means co-acting with said locking parts, and means loosely engaging the laterally movable locking part and holding it against endwise movement in the bore in which the locking device is contained during the actuation of the compressing means.
2. In combination with a member provided with a bore having a lateral opening, of a locking device located in said bore comprising a plurality of parts having co-acting inclined faces and one of which parts is movable laterally of the bore under endwise compression by the other, compressing means co-acting with said locking parts, and means connecting said laterally movable part with said member comprising a detent 60 on one loosely engaging with a seat in the

other whereby the laterally movable part is held against endwise movement in the bore in which the locking device is contained.

3. In combination with a mandrel and a collar thereon for carrying a cutting or creasing device, the said collar having a bore tangential to the mandrel opening and intersecting the same to provide a communicating opening, of a locking device in said bore comprising a plurality of parts having co-acting inclined faces and one of which parts is movable laterally of the bore under endwise compression by another to a position in clamping engagement with the mandrel, compressing means co-acting with said locking parts, and means on the collar loosely engaging the laterally movable locking part and holding it centrally of the mandrel and against endwise movement in the bore.

4. In combination with a mandrel and a collar thereon for carrying a cutting or creasing device, the said collar having a bore tangential to the mandrel opening and intersecting the same to provide a communicating opening, of a locking device in said bore comprising a compression bolt and a plurality of sleeves mounted thereon having co-acting inclined faces, one of said sleeves having an opening of greater diameter than that of the bolt and being movable laterally of the bolt under endwise compression to a position in clamping engagement with the mandrel, and means on the collar loosely engaging the laterally movable locking part and holding it centrally of the mandrel and against endwise movement in the bore.

5. In combination with a mandrel and a collar thereon for carrying a cutting or creasing device, the said collar having a bore tangential to the mandrel opening and intersecting the same to provide a communicating opening, of a locking device in said bore comprising a compression bolt and three sleeves mounted thereon having adjacent co-acting faces inclined in a direction whereby the central sleeve, under endwise compression by the adjacent sleeves, will be moved laterally of the bolt to a position in clamping engagement with the mandrel, said central sleeve having an opening of greater diameter than that of the bolt to permit of such lateral movement, and means on the collar loosely engaging the laterally movable locking sleeve and holding it centrally of the mandrel and against endwise movement in the bore.

6. In combination with a member provided with a bore having a lateral opening, of a locking device located in said bore comprising a compression bolt and a plurality of sleeves mounted thereon having co-acting inclined faces, one of said sleeves having an opening of greater diameter than that of the bolt and being movable laterally of the bolt under endwise compression thereby, and

means loosely engaging said laterally movable sleeve and holding it against endwise movement in the bore in which the locking device is contained during the actuation of 5 the compression bolt.

7. In combination with a member provided with a bore having a lateral opening, of a locking device located in said bore comprising a compression bolt and a plurality 10 of sleeves mounted thereon having co-acting inclined faces, one of said sleeves having an opening of greater diameter than that of the bolt and being movable laterally of the bolt under endwise compression thereby, and

means connecting said laterally movable sleeve, with said member, comprising a detent on one part loosely engaging with a seat in the other part, whereby the sleeve is held against endwise movement in the bore in which the locking device is contained. 15

Signed at Chicago, in the county of Cook and State of Illinois, this first day of July, 20 A. D. 1918.
